(57) CLAIM

We claim the ornamental design for a pitcher, as shown and described.

DESCRIPTION

FIG. 1 is a perspective view of the pitcher, showing our new, original and ornamental design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view with the lid in open position showing partial removal of an interchangeable core.

The broken lines in the figures are for illustrative purposes only and form no part of the claimed design.
